[57] CLAIM

The ornamental design for a communications transceiver set, substantially as shown and described.

DESCRIPTION

FIG. 1 is a perspective view of the back and one side of a communications transceiver set showing our new design;

FIG. 2 is a side view thereof;

FIGS. 3 and 4 are respectively right side and front elevational views of the hanger of the set; the handset component of the set is not shown for ease of illustration;

FIGS. 5 and 6 are respectively back and right side elevational views of the handset, with the hanger not being shown in these, and in FIGS. 7 and 8, for ease of illustration;

FIGS. 7 and 8 are respectively inner and left elevational views of the handset.

The broken line showing of operative dial and display features is for illustrative purposes only and forms no part of the claimed design.
